FOREIGN PATENT DOCUMENTS

WO 2017/163018 9/2017

Primary Examiner — Mimosa De(74) *Attorney, Agent, or Firm* — Leydig, Voit & Mayer, Ltd(57) **CLAIM**

The ornamental design of a double walled locker door, as shown.

DESCRIPTION

FIG. 1 is a rear perspective view of a double walled locker door showing my new design;

FIG. 2 is a rear view thereof;

FIG. 3 is a front view thereof;

FIG. 4 is a bottom view thereof;

FIG. 5 is a top view thereof;

FIG. 6 is a right side thereof;

FIG. 7 is a left side view thereof; and,

FIG. 8 is a front perspective view thereof.

The shading in the drawings represent planar surfaces.

The broken lines shown in the drawings are for illustrating environmental structure and form no part of the claimed design.

1 Claim, 5 Drawing Sheets(56)
